UNITED STATES PATENT OFFICE.

ERIC L. FURBER, OF LIVERPOOL, ENGLAND.

MOISTURE-ABSORBING DEVICE FOR STOPPERED CONTAINING VESSELS.

Application filed December 27, 1923, Serial No. 683,008, and in Great Britain December 27, 1922.

This invention relates to moisture absorbing devices for stoppered containing vessels, of that type in which the moisture absorbing substance is located in the interior of the 5 stopper of the vessel and is detachably held in position therein by a device fitted with springs adapted to grip the wall of the stopper.

The invention is illustrated in the accompanying drawings, in which:—

Figs. 1, 2 and 3 show the arrangement when the moisture absorbing substance is contained in a fabric bag; Fig. 1 being an elevation partly in medial transverse section, 15 Fig. 2 an elevation of the retaining plate with its spring gripping means held in the retracted position; and Fig. 3 is an inverted plan view of the retaining plate and its spring gripping means.

20 Figs. 4 and 5 show a modification in which the spring grips are formed integral with the rim of the retaining plate, Fig. 4 being an elevation in transverse section, and Fig. 5 a plan view in section on the line V. V., of 25 Fig. 4.

Figs. 6 and 7 illustrate a further modification, Fig. 6 being an elevation in transverse section, and Fig. 7 a plan view.

Figs. 8, 9 and 10 show the preferred construction of the receptacle for containing the 30 hygroscopic or drying material, Fig. 8 being an inverted plan view, Fig. 9 a transverse section, and Fig. 10 an arrangement showing the three component parts of the receptacle 35 in the order of assembly.

Figs. 11 to 16 show a modification of the appliance in which the spring grip is detachable from the retaining plate and in which the latter is adapted to retain the receptacle for the hygroscopic material, as 40 shown in Figs. 8, 9 and 10.

Fig. 11 is a general arrangement in part transverse section, Fig. 12 a plan view of the retaining plate, Fig. 13 an elevation on a 45 plane normal to the hinge line of the retaining plate with the receptacle containing the powder in position therein; Fig. 14 an elevation of the retaining plate on a plane parallel to the hinge line; Fig. 15 shows a 50 detail of the hinge part, and Fig. 16 is a partial transverse section to a larger scale.

Referring first to Figs. 1 to 3:—

A is the stopper of the containing vessel to be fitted with the moisture absorbing device, a^1 is the recess formed in the underside of the stopper; B is the perforated retaining

plate, b the perforations therein; and C is a fabric bag containing a hygroscopic substance which is supported in position in the recess a^1 by the retaining plate B. 60

The spring gripping means consist of an open ring b^1 of spring wire attached to the plate B at the centre of its length by a plate as shown at b^2 , its ends being turned up as at b^3 so as to form projections adapted to be 65 grasped between the finger and thumb when the plate B has to be inserted or removed.

The spring ring is preferably composed of steel wire, and to give it increased gripping properties the wire is sheathed with a rubber tube or the like sheath b^4 .

The absorbent pad C is preferably made in the form of a bag composed of a material sufficiently porous to permit access of the air to any suitable deliquescent or hygroscopic 75 substance D contained in the bag but sufficiently close in texture to prevent the escape of the substance. The deliquescent or hygroscopic material contained in the bag may be a mixture of about one third calcium 80 chloride to two thirds keiselguhr.

Figs. 4 to 7 show modifications in the construction of retaining plates and spring gripping means which may be used in place of and in the same manner as the retaining 85 plate B of Figs. 1 to 3.

In Figs 4 and 5 the periphery b^5 of the retaining plate B^1 is turned up as at b^{10} and is slit so as to form a series of circumferentially arranged spring bands b^6 which engage 90 with the interior surface of the recess in the stopper. In this case the plate B^1 is perforated as at b and is provided with a knob b^7 by which it may be withdrawn.

In Figs. 6 and 7 the turned up portions b^5 95 of the retaining plate B^2 are cut through at b^8 and are partially severed as at b^9 from the edge of the plate B^2 so as to form spring bands adapted to engage with the interior surface of the recess in the stopper.

Referring now to Figs. 8 to 10 which show the preferred mode of constructing the container for the hygroscopic substance.

E is a box, which may be of the usual metal construction; e^1 is a bezel adapted to fit the mouth of the box, in effect it forms a lid with the central part of the body cut away as at e^2 . The box is partly filled with a hygroscopic substance D; a strip of porous fabric F such as linen cotton or the like is then stretched across the mouth of the box E, (see Fig. 10), after which the bezel is 100 105 110

fitted so as to grip the fabric between the outside of the box and the inside of the bezel whereby the fabric is stretched across the mouth of the box as shown in Fig. 9 and is retained in position forming a porous wall of the box. The container E may be used instead of the bag C with the modifications of the retaining plate shown in Figs. 1 to 7.

Figs. 11 to 16 show a modification in which the spring gripping means G are detachably secured to the bezel e^1 of the box E which bezel thus forms the perforated retaining plate for the container carrying the hygroscopic substance.

The box E, bezel e^1 and fabric F are as described in connection with Figs. 8, 9 and 10. The wire hoop G is constructed as described in reference to Figs. 1 to 3; that is to say the ends g^4 are turned over to form grips and the wire hoop is sheathed with rubber or the like frictionally gripping material g^2 . The bezel e^1 is provided with a hinge plate e^3 into the hooked part e^4 of which the centre g^3 of the length of the wire G may be entered and by which it is clipped so as to form a detachable connection to the bezel e^1 .

Fig. 11 shows the general arrangement; Fig. 12 is an inverted plan view with the spring grip spread; Figs. 13 and 14 are corresponding elevations and show the box, the bezel and the spring grip with the latter expanded; Fig. 15 shows the spring grip detached; and Fig. 16 shows to a larger scale how the fabric is held in position between the box and the bezel and shows the mode in which the wire G is clipped in the hinge piece e^3 .

Having now fully described my invention, I declare that what I claim, and desire to secure by Letters Patent, is:—

1. In a moisture absorbing device for containing vessels, in combination;—a stopper having in its under side a recess with cylindrical walls; a perforated retaining plate; spring gripping means consisting of an open ended spring hoop of radius greater than that of the cylindrical wall of the recess, attached at a point intermediate its ends to the retaining plate and adapted when the retaining plate is inserted in the recess to follow the contour of and frictionally grip the wall of the recess; a container having

a porous wall and adapted to be supported by the retaining plate in the recess; and a hygroscopic substance in the said container.

2. In a moisture absorbing device for containing vessels, in combination;—a stopper having in its under side a recess with cylindrical walls; a perforated retaining plate; spring gripping means consisting of an open ended spring hoop of radius greater than that of the cylindrical wall of the recess; attached at a point intermediate its ends to the retaining plate and adapted when the retaining plate is inserted in the recess to follow the contour of the wall of recess; a sheathing on the spring hoop of material adapted frictionally to grip the said wall; a container having a porous wall and adapted to be supported by the retaining plate in the recess; and a hygroscopic substance in the said container.

3. In a moisture absorbing device for containing vessels, in combination;—a stopper having a recess in its under side; a perforated retaining plate; spring gripping means consisting of an open ended spring hoop attached at a point intermediate its ends to the retaining plate; a sheathing on the spring hoop of frictionally gripping material; a container comprising a box fitted with a bezel and adapted to be supported by the retaining plate; a porous material stretched across the mouth of the box between the box and the bezel and a hygroscopic substance within the box.

4. In a moisture absorbing device for containing vessels, in combination;—a stopper having a recess in its under side; a perforated retaining plate; a container comprising a box provided with a bezel forming a perforated retaining plate; a porous fabric stretched across the mouth of the vessel between the said mouth and the bezel; a hygroscopic substance within the box; spring gripping means attached to the said bezel-shaped retaining plate consisting of an open hoop attached at a point intermediate its length to the said plate; and a sheathing on the spring hoop of a material adapted to frictionally grip the wall of the recess of the stopper.

In witness whereof I set my hand.

ERIC L. FURBER.
